(57) **CLAIM**

The ornamental design for a wig grip cap, as shown and described.

DESCRIPTION

FIG. 1 is a front elevational view of a first embodiment of a wig grip cap, showing my new design, wherein the wig grip cap is shown deployed on the unclaimed head of a wearer;

FIG. 2 is a rear elevational view thereof;

FIG. 3 is a right side elevational view thereof;

FIG. 4 is a left side elevational view thereof;

FIG. 5 is a top plan view thereof;

FIG. 6 is a front perspective view thereof;

FIG. 7 is a rear perspective view thereof;

FIG. 8 is a front perspective view of the wig grip cap of FIG. 1;

FIG. 9 is a bottom perspective view thereof, wherein a securing feature of the wig grip cap is shown in an unsecured configuration;

FIG. 10 is a front elevational view of a second embodiment of a wig grip cap, showing my new design, wherein the wig grip cap is shown deployed on the unclaimed head of a wearer;

FIG. 11 is a rear elevational view thereof;

FIG. 12 is a right side elevational view thereof;

FIG. 13 is a left side elevational view thereof;

FIG. 14 is a top plan view thereof;

FIG. 15 is a front perspective view thereof;

FIG. 16 is a rear perspective view thereof;

FIG. 17 is a front perspective view of the wig grip cap of FIG. 10; and,

FIG. 18 is a bottom perspective view thereof, wherein a securing feature of the wig grip cap is shown in an unsecured configuration.

The broken lines in the drawings depicting stitching and the human form in FIGS. 1-18 are for illustrative purposes and form no part of the claimed design.
